UNITED STATES PATENT OFFICE

94,149

DESIGN FOR AN INSTRUMENT STAND

Frank Koenigkramer and Frederick Koenigkramer, Cincinnati, Ohio

Application October 12, 1934, Serial No. 53,605

Term of patent 14 years

To all whom it may concern:

Be it known that we, Frank Koenigkramer and Frederick Koenigkramer, citizens of the United States of America, and residents of Cincinnati, in the county of Hamilton and State of Ohio, have invented a new, original, and ornamental Design for an Instrument Stand, of which the following is a specification, reference being made to the accompanying drawing, forming a part thereof.

The figure is a perspective view of an instrument stand showing our new design.

We claim:

The ornamental design for an instrument stand, as shown.

FRANK KOENIGKRAMER.
FREDERICK KOENIGKRAMER.
